ATTORNEY

UNITED STATES PATENT OFFICE.

YOUNG K. BUELL, OF NEW YORK, N. Y.

REINFORCE FOR SHIRTS.

1,316,219.

Specification of Letters Patent Patented Sept. 16, 1919.

Application filed September 4, 1918. Serial No. 252,599.

To all whom it may concern:

Be it known that I, YOUNG K. BUELL, a citizen of the Republic of China; and a resident of the city of New York, borough of 5 Manhattan, in the county and State of New York, have invented a new and Improved Reinforce for Shirts, of which the following is a full, clear, and exact description.

The object of the invention is to provide 10 a new and improved reinforce for negligée shirts and other shirts, arranged to reinforce the neck portion of the shirt and thereby protect this portion against being easily worn through by contact with the collar. 15 Another object is to provide a reinforce of the same material as that of which the shirt body is made, the ornamentation of the reinforce being in register with that of the shirt body so that, in case the latter is worn 20 through, the exposed reinforce has the appearance of the shirt body. Another object is to provide a reinforce which extends all around the neckband and is made in separate pieces, two for the front underneath 25 the shirt body and one at the back underneath the plies of the yoke.

With these and other objects in view, the invention consists of certain novel features of construction as hereinafter shown and described and then specifically pointed out in the claims.

A practical embodiment of the invention is represented in the accompanying drawings forming a part of this specification, in 35 which similar characters of reference indicate corresponding parts in all the views.

Figure 1 is a front elevation of a shirt provided with the improved reinforce;

Fig. 2 is a rear elevation of the same; 40 Fig. 3 is an enlarged cross section of the same on the line 3—3 of Fig. 1; and

Fig. 4 is a similar view of the same on the line 4—4 of Fig. 2.

The body 10 of the shirt is provided at the 45 median line of the front with the multi-ply or reinforced front flaps 11 adapted to overlap and to be fastened together in the usual manner by buttons and buttonholes or other fastening devices 12. The multi-ply neck-band 15 and the multi-ply yoke 16 of the shirt are of the usual construction, and in order to reinforce the body 10 at the front along the neckband up to the yoke 16 use is 55 made of reinforces 20 each extending from the corresponding front flap 11 along the neckband 15 to the yoke 16, as plainly shown

in Fig. 1. Each reinforce 20 is made of a piece of the same shirt material of which the body 10 is made, and the piece is folded over on itself to provide a double thickness and the upper edge is extended between the plies of the neckband 15 and is secured thereto by stitches 21 which also serve to fasten the plies of the neckband 15 together at the base thereof. The lower edge of the reinforce 20 is fastened to the body 10 by a row of stitches 22 which extends to the corresponding flap 11 and to the yoke 16, it being understood that the front end of the reinforce 20 extends between the plies of the flap 11, 60 and the rear end extends between the plies of the yoke 16. Each reinforce 20 has its front member arranged in such a manner that the ornamentations thereof register with the corresponding ornamentations of 65 the body 10 so that in case the body 10 is worn through by the collar, the front member of the reinforce 20 becomes visible and as it is of the same material and of the same ornamentation it is evident that it has the 70 same appearance as the corresponding portion of the body and hence the appearance of the shirt remains practically the same.

A reinforce 25 is arranged between the plies of the yoke 16 and extends along the 75 rear portion of the collar band 15 from one side to the other. This reinforce 25 is of shirt material and preferably of one ply only and its upper edge is fastened in place by the stitches 23 which are used for fastening the upper end of the yoke 16 to the base of the collar band 15. The lower edge of the reinforce 25 is fastened by stitches 24 to the yoke. It will be noticed that the reinforce 25 forms practically a continuation of the 80 front reinforce 20 and hence the entire neck portion of the shirt is reinforced to protect 85 this portion against being easily worn through by contact with the collar. It will 90 be noticed that by the arrangement described the usual construction of the shirt is not interfered with and the reinforcing pieces 20 and 25 can be readily attached to the shirt while the latter is being manufactured.

Having thus described my invention, I claim as new and desire to secure by Letters Patent:

1. The combination with a shirt body having overlapping front flaps, a multi-ply yoke 110 and a multi-ply collar, of front reinforces, underlying the body, each of which is

formed of a piece of shirt material folded over on itself to provide a double thickness and has the front member of said reinforce so disposed that its ornamentations register 5 with the ornamentations of said body, said reinforces extending from the corresponding front flaps along the collar band to the yoke and stitched at their upper edges to said corresponding front flap, said yoke and said 10 collar band, and a row of stitches connecting the lower edges of the reinforce to said corresponding front flap, said body, and said yoke.

2. In combination with a shirt body having 15 overlapping front flaps, and multi-ply yoke and multi-ply collar, of front reinforces, underlying the body, each of which

is formed of a piece of shirt material folded over on itself to provide a double thickness and has the front member of said reinforce 20 so disposed that its ornamentations register with the ornamentations of said body, said reinforces extending from the corresponding front flaps along the collar band to the yoke and stitched at their upper edges to said corresponding front flap, said yoke and said 25 collar band, a row of stitches connecting the lower edges of the reinforce to said corresponding front flap, said body, and said yoke, and a back reinforce interposed between the plies of the yoke and stitched thereto and to the collar band. 30

YOUNG K. BUELL.
